IDENTIFICATION MEANS FOR KEYS
 Caspar J. Ehmcke, 1112 N. La Cienega Blvd.,
 Los Angeles, Calif.
 Filed Mar. 12, 1962, Ser. No. 178,918
 1 Claim. (Cl. 40—330)

The present invention relates to a key identification means whereby a key from a series of keys may be readily located for a particular lock.

Quite often a person will carry a large number of keys on a key ring or a key container and as house keys and door keys generally are quite similar in appearance, often it is difficult to locate the right key for a particular lock.

The present invention serves to identify a key for a particular lock both by feeling with the fingers and by appearance. The invention gives each key a distinguishing characteristic.

An object of the present invention is to provide a key identification means characterized in that the said means has prominence, legibility, convenience and neatness.

A further object is to provide a key identification means which may be easily applied to a key and which when applied does not absorb force on the bow whereby the key bow may be gripped firmly.

Another object is an identification means for keys which will indicate the particular key for a given lock such as a key for motel, hotel, door of a house, a garage, automobile, etc.

A further object of the invention is to provide a key identification means which is inexpensive in cost of manufacture, easily applied to the bow of a key, does not detract from the key appearance and which is generally superior to key identification means now known to the inventor.

In the drawing:

FIGURE 1 is a side elevation of a key provided with identification means embodying the invention;

FIGURE 2 is an edge elevation of the key shown in FIGURE 1;

FIGURE 3 is a fragmentary sectional view on the line 3—3 of FIGURE 1, and on an enlarged scale;

FIGURE 4 is a perspective view of one form of key identification means showing the two parts thereof; and,

FIGURES 5 to 10 inclusive are illustrative of other forms of identification means for a key.

Referring now to the drawing, I have shown in FIGURE 1 one form of key having a configuration of a type generally used for locks of the type which are employed in doors for a house, factory, motel and the like. Automobile keys are of a different configuration, as a rule, and for that reason may be distinguished save and except that usually there are three keys; to wit, for the ignition, glove compartment, and rear compartment. Usually the automobile keys have the same appearance and are therefore, difficult to distinguish, often requiring that each key be tried in a lock before the proper key is found.

The key of FIGURE 1 is purely illustrative and will apply to any type of key and in this respect the key includes a bow 1 at one end of a shank or stem 2, the shank being provided with wards 3 and usually with stops 4 and 5 on the shank adjacent the bow for the purpose of limiting key insertion within the keyhole of a lock. The bow 1 is provided with a hole 6 whereby a chain such as shown at 7 in FIGURE 3 may be passed through the hole for securing a key. The chain 7 may hold or secure a multiple number of keys. So-called key containers are largely used by individuals and the securing means in the key container may be passed through the hole 6. Unless the keys are arranged in a given sequence or order which a person would have

2

to remember, the keys, even if of different size, often are difficult to find for a given lock. Accordingly, the present invention provides an identification means which will distinguish a key for a given lock both by feel and appearance. Thus, in FIGURE 4 I have shown an identification means having two parts 8 and 9. This identification means comprises an embossment, boss, or protuberance 8 provided with a shank 10 extending from one side of the embossment for reception in the transverse bore 11 of embossment 9. The means for securing together the two identification means in the form of embossments 8 and 9 may take various forms and in FIGURE 4 the shank 10 is tubular in form, the hole therein communicating with hole 12 of the embossment whereby the shank 10 may be passed through the hole 6 of the key bow and be secured in the hole 11 of embossment 9. The external surface of the shank 10 is screw threaded as shown at 13 and the wall bounding the hole 11 is screw threaded, as shown at 14, for reception of the screw threaded shank. As shown in FIGURES 1 to 4 inclusive, the embossment or identification means is "H" in form. In the present instance the H may be formed from a square or rectangular block having upper and lower recessed portions 15 and 16 and provided with a backing wall 17 to which the shank 10 is secured. The diametrically opposed indentations 15 and 16 facilitate firm tightening of the members 8 and 9 on the key 1. The same construction would be used for the letter of embossment 9. Thus when the threads 13 of shank 10 engage the threads 14, the embossments 8 and 9 are held against opposite surfaces of the bow 1, as shown in section in FIGURE 3. The hole 12 may be reduced in diameter over the normal diameter of the hole 6 in the bow. As a rule the hole 12 will be of sufficient diameter to accommodate a chain 7 or other key securing device. If not, it is within the purview of my invention to enlarge the diameter of the hole in the bow of a key. By way of illustration the H might serve to indicate a house key such as to the front door lock. Obviously, the fingers when passed over the identification means would immediately detect the H-shape formation and thereby distinguish the key from other keys on a key ring or chain. If the key could be observed, then the H would be easily seen and the key identification determined. It is within the purview of my invention to phosphorize the identification means so that the identification means may be seen in the dark. Or the identification means may have a color. The thickness of the embossment can vary but should be sufficient to permit the fingers to readily determine the nature thereof. In place of using the screw threaded shank 10, I may of course, use other means for securing the two parts of the identification means together on the bow of the key such as for instance a snap catch, rivet, or other means and the embossment may be a plastic, metal, or other suitable and durable material. It is to be particularly noted that the embossments described do not absorb force on the bow of the key to the end that the bow of the key may be gripped firmly by a person using the key. This type of identification means does not alter the key bow in the least by providing extraneous means which is shaped to overlie the key bow or to follow the outline of the key bow.

The remaining figures show different forms of identification means and FIGURES 5 and 6 show the embossment in the form of an annulus. One part would be provided with a screw threaded shank and the opposite part formed to receive the screw threaded shank. Such a device might be used to indicate an office key as the embossment has the appearance of the letter "O."

In FIGURES 7 and 8, the embossments have radial spokes on the front faces, as shown at 20 and such an

identifying means may represent the key to a spare tire lock, the embossment as before may have a screw threaded shank for reception in a screw threaded bore, the two halves constituting the identification means, being secured on opposite sides of the key bow.

In FIGURE 9 the embossment is star shaped in outline having a central bore, the embossment has a star shaped outline 25 provided with a central bore 26 to which a shank similar to that shown at 10 is secured, the shank being threaded the same as shown in FIGURE 4 at 13 for reception in the threaded bore in a further star-shaped embossment. This might be indicative of a key carried by a police officer to indicate a handcuff lock or other device.

In FIGURE 10 the embossment 30 is of diamond shape of which there are two embossments connected together in a manner similar to that shown in FIGURE 4. The diamond embossment would indicate to a baseball player the key to a locker or other device.

The principle of my invention is to provide an identification means attached through the hole of the bow of a key which indicates the key purpose both by appearance and by feel.

The operation, uses and advantages of my invention are undoubtedly clear from the description before given as to the character of the identification means, its method of securing to the bow of a key and the function to be performed thereby. As previously stated, the embossments need not be of great thickness but of a thickness sufficient to readily show the character of the emboss-

ment either by feel or sight, and which does not modify the key structure.

I claim:

5 generally flat key, the bow having a hole therethrough, comprising: a pair of similar embossments each having a through aperture and characteristics identifiable by feel and by appearance, one embossment provided with a tubular externally threaded shank extending from the inner surface of the embossment for passage through the hole of the key bow, the second embossment having its aperture provided with internal screw threads for receiving the screw threaded shank whereby the two embossments may be secured together with the key bow therebetween, the outer margin of each embossment lying entirely within the margin of the key and each embossment having diametrically opposed indentations extending to the edge of the embossment to facilitate firm tightening of the embossments on the key.
